REVERSIBLE ROTARY MOTOR

Paul Van Sittert, Shaker Heights, Lloyd G. Speth, East Cleveland, and John H. Engeln, Cleveland, Ohio, assignors to The Cleveland Pneumatic Tool Company, Cleveland, Ohio, a corporation of Ohio

Original application February 23, 1939, Serial No. 257,824. Divided and this application May 17, 1941, Serial No. 394,012

7 Claims. (Cl. 121—34)

This application is a division of application, Serial No. 257,824, filed February 23, 1939.

This invention relates broadly to rotary motors, but more particularly to fluid actuated rotary motors of the reversible type.

One object of this invention is to produce a fluid actuated rotary motor of the reversible type with manually operable means for controlling the direction of rotation of the motor.

Another object of this invention is to construct a fluid actuated rotary motor of the reversible type wherein the parts are arranged and disposed in a manner producing a compact assembly which is strong, durable and efficient.

Other objects and advantages more or less ancillary to the foregoing reside in the specific construction and aggroupment of the elements peculiar to this structure, as will become apparent from a more complete examination of this specification.

In the drawing:

Fig. 1 is a longitudinal sectional view of a rotary motor embodying the invention.

Fig. 2 is a sectional view taken in a plane indicated by line 2—2 in Fig. 1.

Fig. 3 is an enlarged sectional view indicated by line 3—3 in Fig. 2.

Figs. 4 and 5 are views similar to Fig. 3 illustrating some of the movable parts in different positions.

Fig. 6 is an enlarged side view of one of the parts shown in Fig. 2.

Referring to the drawing, 220 represents a motor housing having lateral extension 21 to which is secured by cap screws 22 a handle 23 extending laterally from the motor housing and having a handle grip 24 rotatable thereon. Rotatable within the extension 21, there is a valve 225 having a stem 26 extending into the handle 23, which stem is secured to the handle grip 24 by a screw 27 movable within a slot provided through the handle 23. In the handle 23, there is also a throttle valve 28 operatively associated with the handle grip 24 through a pin connection 29 arranged and disposed in a manner causing longitudinal movement of the throttle valve 28 upon rotary movement of the handle 24. The handle 23 is terminated by a motive fluid connection 30 through which motive fluid may be admitted into the handle where its admission into the motor is controlled by the throttle valve 28 which is normally maintained against a valve seat 31 by a compression spring 32. From the throttle valve 28 motive fluid may be admitted into an inlet chamber 33 formed

within the motor housing 220 via an inlet passage 34 provided through the valve 225.

Opening into the inlet chamber 33, there is a passage 36 controlled by a centrifugally operated 5 governor valve 37 movable into open or closed position relative to an annular groove 38 affording communication between the passage 36 and an inlet passageway 239 formed within the extension 21 and controlled by the valve 225, which valve is rotatably mounted within a bushing 240 provided with four equally spaced radial ports 241, 242, 243 and 244, the port 244 being in constant communication with the passageway 239, while the port 242 is in communication with an 15 exhaust port 245.

Vertically disposed within the housing 220, there is a stator in the form of a cylindrical sleeve 46 having rotatable therein a rotor 47 formed with shafted end portions 48 and 49, each 20 journaled within an adequate bearing 50, the end portion 48 being provided with a pinion 51. The rotor 47 is mounted eccentrically relative to the center axis of the stator 46 in line contact with the inner wall thereof as at 54 and carries radially 25 movable vanes 55 capable of operative engagement with the inner wall of the stator 46, which stator is provided with two inlet grooves 56 and 57, one located on each side of the bearing line 54 and two sets of exhaust ports 58 and 59, one 30 located on each side of the bearing line 54. Each set of exhaust ports includes a plurality of longitudinally spaced ports as shown in dotted lines at 59 in Fig. 1.

Rotatably mounted within the housing 220 35 parallel to the rotor 47, there is a tool receiving spindle 96 operatively connected to the rotor 47, or more particularly to the pinion 51 thereof by a train of gears, not shown. Axial pressure may be exerted on the spindle 96 by means of a screw 40 94 rotatable through a handle or spider 93 affixed thereto by a cross pin 95.

In the upper end of the motor housing 220, there is accommodated a centrifugal governor 72 operatively associated with the governor valve 45 37 through a lever 73.

The peripheral wall of the valve 225 is provided with two diametrically opposed slots 70 and 71, the purpose of which will be explained later. Between the slots 70 and 71 the peripheral wall of the valve is also provided with two 50 smaller flats 83 and 84 disposed at 90° from one another and capable of registration with the radially disposed ports 241, 244 and 243 formed through the valve bushing 240. Internally, the casing 220 is provided with passageways 268 and

269, the former being in constant communication with the valve bushing port 241 and the latter with the port 243.

Located within the passageway 268, there is an arm 85 pivoted on a cross pin 86 and formed with an elongated exhaust control end 87 shaped to fit on the stator 46 to cover the exhaust ports 58 one of which is shown in Fig. 2. The other end 88 of the arm 85 extends through the port 241 of the valve bushing 240 in operative engagement with the normal peripheral wall of the valve 225.

Between the pin 86 and the end 88, the arm 85 is preferably reduced in cross section to enable a slight flexing of the arm while positioned as shown in Fig. 2, thereby assuring a fluid tight engagement of its end 87 with the stator 46. Located within the passageway 269, there is a similar arm 89 pivotally mounted on a cross pin 90 and formed adjacent the exhaust port 58 with a controlling end 91. The other end 92 of the arm 89 extends through the port 243 of the valve bushing 240 for engagement with the valve 245.

In the operation, the throttle valve 28 may be moved into open position relative to the valve seat 31 against the compression spring 32 by simply rotating the handle grip 24 in one or the other direction, thereby rotating the valve 225 connected to the handle grip 24 by the screw 27 into the position shown in Fig. 3 or 4, thus admitting motive fluid into the inlet chamber 33 through the port 34 of the valve 225, which will act on the governor valve 37 to shift it into open position as shown in Fig. 1 and enable admission of the motive fluid into the passageway 239 via the groove 38. This longitudinal movement of the throttle valve 28 upon rotary movement of the handle grip 24 is obtained by virtue of a helical groove formed within the handle within which is mounted the screw 29 connecting the handle grip to the throttle valve, and since that construction does not form a part of the present invention, no further description of the same is thought necessary.

With the valve 225 positioned as shown in Fig. 3, motive fluid from the passageway 239 is free to flow into the passageway 268 through the valve bushing port 244, the valve slot 70 and the valve bushing port 241. From the passageway 268, motive fluid will be admitted into the stator 46 through the inlet slot 56, thereby acting on the vanes 55 for imparting rotation to the rotor 47 in a counterclockwise direction in Fig. 2. In this instance, the arm 85 has its end 88 engaging the normal peripheral wall of the valve 225 causing the other end 87 of the arm to be pressed against the stator 46 for closing the exhaust ports 58. In this position of the arm 85, the other arm 89 has its end 92 engaging the flat 84 formed on the valve 225, thereby enabling its other end 91 to be moved away from the stator 46 by the action of the pressure fluid exhausting through the ports 59, which ports together with the stator slot 57 opens into the passageway 269 now in communication with the exhaust port 245 via the valve bushing port 243, the valve slot 71 and the valve bushing port 242. In other words, as the rotor 47 is actuated in a counterclockwise direction in Fig. 2, the pressure fluid acting on the end 91 of the arm 89 will shift that end into open position relative to the exhaust ports 59, thereby enabling the exhaust of the motive fluid through the ports 59 and also through the slot 57 via the passageway 269.

When it is desired to rotate the motor in the

other direction, the valve 225 may be rotated into the position shown in Fig. 4 for admitting motive fluid from the passageway 239 into the passageway 269 via the valve bushing port 244, the valve slot 71 and the bushing port 243. From the passageway 269 motive fluid will flow into the stator 46 through the slot 57 to act on the vanes 55 for actuating the rotor in a clockwise direction in Fig. 2. In this instance, the end 91 of the arm 89 engages the normal peripheral wall of the valve 225, thus causing the forcible engagement of the arm's end 91 with the stator 46 for the closing of the exhaust ports 59. In this position of the arm 89, the arm 85 has its end 88 engaging the flat 83 formed on the valve 225, thus allowing motive fluid exhausted through the ports 58 to act on the end 87 of the arm 85 to move that end away from the stator 46 for opening the exhaust ports 58 into the passageway 268 and enabling together with the groove 56, also opening into the passageway 268, exhaust of the motive fluid from the stator 46. In this instance, port 268 is in communication with exhaust port 245 through the valve bushing port 241, the valve slot 70 and the bushing port 242.

With the parts positioned as shown in Fig. 5, the corresponding position of the handle grip 24 will cause the throttle valve 28 to remain closed relative to the valve seat 31, while the ends 88 and 92 of the arms 85 and 89 respectively engage the normal peripheral wall of the valve 225 for maintaining the arms in closed position relative to the exhaust ports 58 and 59.

Although the foregoing description is necessarily of a detailed character, in order to completely set forth the invention, it is to be understood that the specific terminology is not intended to be restrictive or confining and it is to be further understood that various rearrangements of parts and modifications of structural detail may be resorted to without departing from the scope or spirit of the invention as herein claimed.

We claim:

1. In a fluid actuated rotary motor of the reversible type, the combination with a housing, of a stator within said housing having a rotor chamber, a rotor operatively mounted in said chamber, means for admitting and exhausting motive fluid into and from said chamber including a pair of inlet and a pair of outlet ports, a rotatable valve for selectively controlling admission of motive fluid through one or the other of said inlet ports, outlet ports controlling means pivotally mounted within said housing engageable with said stator for closing one or the other of said outlet ports, and means on said valve engaged by said outlet ports controlling means for actuating the same upon rotation of said valve.

2. In a fluid actuated rotary motor of the reversible type, the combination with a housing, of a stator within said housing having a rotor chamber, a rotor operatively mounted in said chamber, a rotatable handle extending from said housing, means for admitting and exhausting motive fluid into and from said chamber including a pair of inlet and a pair of outlet ports, outlet ports controlling means pivotally mounted within said housing engageable with said stator for closing one or the other of said outlet ports, and means in said handle engaged by said outlet ports controlling means for actuating the same upon rotation of said handle.

3. In a fluid actuated rotary motor of the reversible type, the combination with a housing, of a stator within said housing having a rotor

chamber, a rotor operatively mounted in said chamber, means for admitting and exhausting motive fluid into and from said chamber including at least two outlet ports, outlet ports controlling means including an arm for each outlet port pivotally mounted in said housing, said arm having one end movable into opened or closed position relative to its respective outlet port, and movement effecting means for said arm operatively engaged by the other end thereof.

4. In a fluid actuated rotary motor of the reversible type, the combination with a housing, of a stator within said housing having a rotor chamber, a rotor operatively mounted in said chamber, means for admitting and exhausting motive fluid into and from said chamber including a pair of inlet and a pair of outlet ports, outlet ports controlling means including a pair of arms pivotally mounted in said housing, said arms having one end movable into opened or closed position relative to said outlet ports, and movement effecting means for said arms operatively engaged by the other ends of said arms for concurrently closing one and opening the other of said outlet ports.

5. In a fluid actuated rotary motor of the reversible type comprising a stator having a rotor operatively mounted therein and ports through the stator including at least two outlet ports, means for controlling said outlet ports including a pair of pivotally supported arms having one end movable into opened or closed position relative to said outlet ports, and cam means opera-

tively engaged by the other ends of said arms for concurrently closing one and opening the other of said outlet ports.

6. In a fluid actuated rotary motor of the reversible type comprising a stator having a rotor operatively mounted therein and ports through the stator including at least two sets of outlet ports, each of said sets including a plurality of longitudinally spaced ports, means for controlling said outlet ports including a pair of pivotally supported arms each having one end adapted to close all the ports of its respective set, and means operatively engaged by the other ends of said arms for closing said ports.

7. In a fluid actuated rotary motor of the reversible type, the combination with a casing, of a stator within said casing having a rotor chamber, a rotor operatively mounted in said chamber, a pair of passageways in said casing leading to said stator, a rotatable valve for selectively controlling admission of motive fluid to one or the other of said passageways, an inlet and an outlet port through said stator connecting said chamber to each of said passageways, a pivotally supported arm within each of said passageways having one end movable into opened or closed position relative to said outlet port, and means on said valve engaged by the other end of said arm for actuating said arm upon rotation of said valve.
